UNITED STATES PATENT OFFICE.

EDWARD SPENCER PIPER, OF TORONTO, CANADA.

CUPOLA TAIL-LAMP.

SPECIFICATION forming part of Letters Patent No. 616,966, dated January 3, 1899.

Application filed April 22, 1898. Serial No. 678,457. (No model.)

To all whom it may concern:

Be it known that I, EDWARD SPENCER PIPER, manufacturer, of the city of Toronto, in the county of York and Province of Ontario, 5 Canada, have invented a new and Improved Cupola Tail-Lamp, of which the following is a specification.

The object of my invention is to devise a cupola tail-lamp for railway-trains which may 10 be caused to show red to the rear and white or green to the front when the train is on the main line or green to the rear and white or green to the front when the train is on a siding; and it consists, essentially, of a lamp- 15 casing connected to the roof of a car above an opening therein and provided with lenses in front and rear and of a revoluble frame supported therein carrying two green glasses or a green and a white diametrically disposed 20 and a red and a white or green glass diametrically disposed between them, suitable indicating and locking mechanism being provided, whereby a trainman may set the said frame to show the desired signals, substantially as hereinafter more specifically 25 described and then definitely claimed.

Figure 1 is a perspective view, partly broken away, of my improved lamp. Fig. 2 is a vertical section of the same. Fig. 3 is a bottom 30 plan view of the same. Fig. 4 is a sectional plan view taken through the lenses.

In the drawings like letters of reference indicate corresponding parts in the different figures.

35 A is the lamp-casing, which is provided with the usual means of ventilation. Openings are formed at the front and rear of this casing which are glazed with the lenses I. The casing is provided at its base with an inwardly-projecting flange B, which outside the casing is provided with suitable screw-holes for connection to the edges of a suitable opening formed in the car-roof C. The inwardly-projecting portion of the flange is shouldered 40 at a. Resting on the flange within the shoulder is a ring D, which is held in place by means of clips E, secured to its lower surface and extending beneath the flange B. Extending upwardly from this ring are two or more 45 standards F, which support the circular frame G. This frame has four circular openings formed therein, behind which are supported

the colored glasses H H' H'' H'''. The glasses H and H' are red and white or green, respectively, and the glasses H'' and H''' are green 55 or green and white.

By revolving the ring D it is evident that the red and white glasses may be brought in front of either of the lenses of the casing or that the green glasses may be made to occupy 60 the same position. In order to lock the ring in any of the positions described, I provide a spring-operated plunger J, which is connected to the under side of the ring and extends below the flange B. In the flange are formed 65 four holes b, with any one of which the plunger J may be engaged.

K is a lamp having a flanged skirt L connected thereto, which when the lamp is pushed up through the ring D engages the 70 lower side thereof, as shown in Fig. 2.

M are spring-catches connected to the sides of the lamp and arranged to engage the inner edge of the ring D, as shown. By pressing inwardly these spring-catches the lamp may 75 be readily removed for lighting and as readily replaced.

In accordance with the recently-adopted code of signals all railway-trains are required to carry lamps upon the top of the rear car, 80 showing red to the rear and white or green to the engineer when the train is on the main line. They are also required to show a green light to the rear and a green or white light to the engineer when on a siding. 85

With a lamp such as described by revolving the circular frame carrying the colored glasses the required signals may be given. If the red and white lights were fixed so as always to show to the same ends of the car, the lights 90 would be wrong unless the car were turned on arriving at the end of its journey in one direction. With my improved lamp it is immaterial whether the car be turned or not, as by revolving the circular frame the red and 95 white or green lights may be shown as required. In order that the trainman within the car may see how the lamp is set, I prefer to paint on the under side of the ring D colored sections similar in color to the glasses 100 immediately above them, so that the position of the colored sections on the ring shows exactly the position of the glasses above.

What I claim as my invention is—

1. As a cupola tail-lamp, a lamp-casing provided with lenses in front and rear and a shouldered flange at its base, in combination with a ring resting on the said flange within the shoulder; means for holding the ring on the flange; a frame connected to the said ring and carrying two green glasses or a green and white diametrically disposed, and a red and white or green glass diametrically disposed between them; a lamp detachably supported within the said ring; a spring-actuated plunger carried by said ring and adapted to engage holes formed in the bottom flange of the lamp-casing, substantially as and for the purpose specified. 35
- 5 2. As a cupola tail-lamp a lamp-casing provided with lenses in front and rear and an inwardly-projecting shouldered flange at its base in combination with a ring resting on the said flange within the shoulder; clips secured to the ring and extending under the flange; a frame connected to the said ring and carrying two green glasses or a green and white diametrically disposed, and a red and a white or green glass diametrically disposed 40 between them; a lamp detachably supported within the said ring, and means for locking the given color of glass in front of any given lens, substantially as and for the purpose specified. 45
- 10 3. As a cupola tail-lamp a lamp-casing provided with lenses in front and rear and an inwardly-projecting shouldered flange at its base in combination with a ring resting on the said flange within the shoulder; clips se- 50
- 20 cured to the ring and extending under the flange; a frame connected to the said ring and carrying two green glasses or a green and white diametrically disposed, and a red and a white or green glass diametrically disposed 55 between them; a lamp detachably supported within the said ring; a spring-actuated plunger carried by said ring and adapted to engage holes formed in the bottom flange of the lamp-casing, and colored quadrants painted 60 on the bottom of the ring, substantially as and for the purpose specified. 65
- 25
- 30

4. As a cupola tail-lamp a lamp-casing provided with lenses in front and rear and an inwardly-projecting shouldered flange at its base in combination with a ring resting on the said flange within the shoulder; clips se- 50
